UNITED STATES PATENT OFFICE.

JOHN EDWARD NEALY, OF NEW YORK, N. Y.

COIN-CONTROLLED MECHANISM.

1,171,456.

Specification of Letters Patent. Patented Feb. 15, 1916.

Application filed May 17, 1915. Serial No. 28,580.

To all whom it may concern:

Be it known that I, JOHN EDWARD NEALY, a citizen of the United States, residing at New York, in the county of New York and 5 State of New York, have invented certain new and useful Improvements in Coin-Controlled Mechanism, of which the following is a specification.

This invention relates to vending machines and more particularly to coin controlled mechanisms used in conjunction therewith.

In my co-pending applications, Serial 10 Numbers 28,579 and 28,581, I have disclosed 15 in the one case, a vending machine adapted and arranged when a coin is deposited therein to render accessible a flexible table and a deck of cards together with means for holding the table in distended position so 20 that in exchange for a coin means are provided for playing a game of cards as before stated; and in the other a vending machine. The present application is intended to cover particularly the coin controlled 25 mechanisms employed in conjunction with an apparatus of the type above outlined.

A further object of the invention is to provide means for registering the number of coins deposited.

30 Further objects and advantages of the invention will be set forth in the detailed description which now follows.

In the accompanying drawings: Figure 1 is a front elevation of a vending machine 35 having the coin controlled mechanism applied thereto; Fig. 2 is a vertical sectional view upon line 2—2 of Fig. 1; Fig. 3 is a vertical transverse section looking from the rear toward the front with the locking 40 bar in its lowered position; Fig. 4 is a like view with the lock bar in its raised or unlocked position; Fig. 5 is a view partly in plan and partly in horizontal section; Fig. 6 is a horizontal sectional view; and, Fig. 45 7 is a detail view of a lock bar hereinafter described.

Like numerals designate corresponding parts in all of the figures of the drawing.

Referring to the drawing, the numeral 50 5 designates a casing divided by a horizontal wall 6 into a small upper compartment 7 and a lower compartment 8. The front of the lower compartment is closed by a hinged, spring actuated door 9 and carries 55 upon its inner face a rack 10 for the reception of a deck of cards. A folded flexible

table is indicated at 11 but since said table forms no part of the present invention, further description thereof in this application is omitted. An L shaped strip 12 provides 60 a housing for a vertically movable lock bar 13. This lock bar is slotted at 14 and engages guide studs 15 in such manner that it is capable of a limited vertical movement as before stated. This lock bar is cut 65 out at 16 to provide tongues 17 arranged to pass through the horizontal portions 18 of ears 19, said ears being carried by the door. The upper end of the lock bar is bent to provide a horizontal extension 13^a. This 70 extension is notched at 13^b for a purpose hereinafter set forth.

The rear and side walls of the casing 5 are extended upwardly beyond the horizontal wall 6 as indicated in Fig. 3 but the door 9 75 terminates at substantially the level of the wall 6 and the casing proper has no top wall. Upon the contrary, the front and top of the casing 5 are closed by an L shaped member comprising a front wall 19^a and a top wall 80 20. The side walls of the casing 5 carry straps 21 provided with horizontal extensions 22 beneath which the edges of the top 20 engage. A lock 23 controllable by a key when placed in key-hole 24 is so arranged 85 that this bolt 25 may be projected into a recess 26 of the side wall of the casing so that the L shaped member is thereby locked in place. All of the coin controlled mechanism 90 is carried by, and movable into place with this L shaped member, and this L shaped member completes the compartment 7 which thereupon becomes a coin receptacle. A coin slot 27 provides means for depositing a coin in coin chute 28. A coin deposited 95 in said coin chute will rest upon a tail 29 of a lever 30. This lever is pivoted at 31 and is forked at 32 to engage a stud 33 of a sleeve 34. This sleeve carries circumferential flanges 35 which when the L shaped 100 member is slipped into place, engage above and below the horizontal extension 13^a of the locking bar 13. The sleeve 34 is guided upon a pin 36 carried by a stud 37 projecting from the wall 19. A spring 38 normally tends to force this sleeve downwardly, said 105 spring bearing between extension 39 of stud 37 and a pin 40 carried by the sleeve. A link 41 is connected to the stud 33 and pivotally engages the crank arm 42 of a counter 43. 110 When a coin rests in the position illustrated in Fig. 3 it lies in a path of a curved lever

44 carried by the shaft of a handle 45 so that when said handle is actuated, the curved lever acts upon the coin and forces said coin downwardly to depress the tail 29 of lever 5 30. This lifts the forked end of said lever, lifts the sleeve 34 against the tongue of spring 37 and through the medium of the flanges 35 and extension 13^a lifts the locking bar to carry the tongue 17 out of engagement with ears 18 to thereby unlock the door. After the tail 29 has moved downwardly a predetermined distance, the coin moves past the point *a* of the coin chute to such an extent that it is projected from the 15 coin chute and falls upon the bottom of compartment 7. A spring 46 is wound upon the pivot of lever 44 and normally tends to move said lever to the position illustrated in Fig. 3.

20 The counter provides means for registering the number of coins deposited, so that a check upon the collectors of such coins may be had.

While the elements shown and described 25 are well adapted to serve the purpose for which they are intended, it is to be understood that the invention is not limited to the precise construction set forth, but that it includes within its purview such changes as 30 come within the spirit as well as the terms of the appended claims.

Having described my invention, what I claim is:—

1. In a device of the character described, 35 the combination with a vertically disposed coin chute opened at its upper and lower ends, of a lever pivoted outside of said chute, and having one end disposed beneath the lower end of said chute, a manually oper- 40 able oscillatory shaft disposed outside of

said chute, a curved lever mounted thereon and movable therewith, said coin chute having an opening in one of its sides through which said lever swingingly moves, said lever having a convex upper face and the 45 movement of said lever being in an arcuate path and across said coin chute.

2. In a device of the character described, the combination with a pivoted lever having a curved upwardly directed tail, of a coin 50 chute beneath which the tail end of said lever is disposed, a second lever which acts in said coin chute to force the coin deposited therein against the first named lever, a handle for actuating said second lever, a vertical 55 movable sleeve, a stud carried thereby, said stud engaging in a recess formed in the first named lever, and means normally tending to force said sleeve downwardly.

3. In a device of the character described, 60 the combination with a pivoted lever having a curved upwardly directed tail, of a coin chute beneath which the tail end of said lever is disposed, a second lever which acts in said coin chute to force the coin deposited 65 therein against the first named lever, a handle for actuating said second lever, a vertical movable sleeve, a stud carried thereby, said stud engaging in a recess formed in the first named lever, means normally tending to 70 force said sleeve downwardly and a fixed guide rod upon which said sleeve is slidably disposed.

In testimony whereof I affix my signature in presence of two witnesses.

JOHN EDWARD NEALY.
